DESIGN FOR A LAYOUT SCALE

Kurt Jaeger, Plainfield, N. J.

Application June 14, 1944, Serial No. 113,990

Term of patent 14 years

(Cl. D52—1)

To all whom it may concern:

Be it known that I, Kurt Jaeger, a citizen of the United States and resident of Plainfield, in the county of Union, in the State of New Jersey, have invented a new, original, and ornamental Design for a Layout Scale, of which the following is a specification, reference being had to the accompanying drawing, forming a part thereof.

Fig. 1 is a plan view of a layout scale, showing my new design; and Fig. 2 is an edge elevational view of the same.

I claim:

The ornamental design for a layout scale, as shown.

KURT JAEGER.
